UNITED STATES PATENT OFFICE.

JOHN G. SODERBERG AND WILLIAM W. ROBERTSON, OF WORCESTER, MASSACHUSETTS,
ASSIGNORS TO CROMPTON & KNOWLES LOOM WORKS, OF WORCESTER, MASSACHUSETTS, A CORPORATION OF MASSACHUSETTS.

YARN-TUBE FRAME FOR LOOMS.

Application filed May 19, 1923. Serial No. 640,250.

This invention relates to a yarn tube frame of the general type commonly used in Axminster carpet looms and in other similar looms.

5 It is the general object of our invention to improve the construction of the brackets or supports which connect the tube frames to the transporting pattern chains and which provide bearings for the ends of the spools 10 on which the yarn is wound.

With this general object in view our invention consists in providing a tube frame bracket or support of an improved and simplified construction, with the parts so designed that they may be easily and cheaply assembled, and in providing an improved means of assembling the parts, so that they will be firmly secured against accidental displacement.

20 In one embodiment of our invention, an integral supporting bracket and spool bearing plate is held in position against the end of the tubular member by clamping devices integral with the tubular member.

25 In another embodiment of our invention, an attaching plate is permanently secured to each end of the tubular member in some convenient manner, as by bending portions of the tubular member to embrace the plate, 30 and a second or supporting plate is detachably secured to each first named plate and cooperates with the usual spring hook to sustain and position the tube frame.

A third form of our invention provides 35 means for clamping the spring hook between the attaching and supporting plates.

Our invention further relates to arrangements and combinations of parts which will be hereinafter described and more particularly pointed out in the appended claims.

Three forms of the invention are shown in the drawings, in which

Fig. 1 is a side elevation of a form of our invention in which the supporting bracket is formed as a single plate permanently secured to the end of the tubular member;

Fig. 2 is an end elevation of this form of our invention;

Fig. 3 is a partial perspective view with 50 the parts separated;

Fig. 4 is a sectional plan view, taken along the line 4—4 in Fig. 2;

Fig. 5 is a front elevation of a second

form of our improved tube frame construction;

55

Fig. 6 is an end elevation of the parts shown in Fig. 5;

Fig. 7 is a partial perspective view of one end of the tubular member;

60

Fig. 8 is a detail sectional view taken along the line 8—8 in Fig. 6;

Fig. 9 is a side elevation of a third form of our invention;

Fig. 10 is an end elevation thereof;

Fig. 11 is a perspective view of one end 65 of one of the tubular members used with this form of our invention;

Figs. 12 and 13 are detail sectional views taken along the lines 12—12 and 13—13 in Fig. 10, and

70

Figs. 14, 15 and 16 are detail views to be described.

Referring first to Figs. 1—4, inclusive, we have shown a portion of a rectangular tubular member 20 to which the yarn tubes 75 21 are secured in the usual manner. The upper and lower walls of the tubular member 20 are cut away at each end to form side projections 22 and recessed portions 23.

A supporting plate or bracket 24 is formed 80 at its upper end in accordance with the usual practice and provides a spool bearing 25 and an outer or chain-engaging portion 26 which cooperates with a spring 27 in attaching the tube frame to a transporting pattern chain.

85 The bracket 24 is provided with notches 28 on each side thereof, adapted to receive the projections 22 of the tubular member 20 when the parts are assembled, with the brackets or plates 24 abutting the end surfaces of the recessed portions 23 of said member. After the parts are thus assembled, the projections 22 are bent inward around the plate or bracket 24 as clearly shown in Fig. 4, embracing the plate and holding it firmly against the end of the member 20.

90 The spring 27 may be secured against the outer face of the projections 22 by one or more screws 29 threaded into the bracket 24.

95 The spring projects through a slot 30 in the bracket and is thus held from lateral displacement. It will be evident that the brackets 24 are permanently secured to the ends of the tubular member 20 by the co-action of integral parts of the tubular mem-

ber and bracket and without the use of any separate or additional fastening devices.

In the form shown in Figs. 5-8, inclusive, the bracket or support is made in two parts, 5 with an attaching plate 35 secured to the end of the tubular member 36 by projecting portions 37 extending through notches 38 (Fig. 14) and embracing the plate 35, as indicated in Fig. 8.

10 A second or supporting plate 40 is detachably secured to the attaching plate 35 in any convenient manner as by screws 41. The plate 40 is also notched or recessed as shown at 42 in Fig. 15 and fits between the 15 ends of the bent projections 37. The usual spring 43 is secured to the outside of the supporting plate 40 by screws 44 and extends upward through a slot 45 in the supporting plate 40. The upper end of the attaching plate 35 is commonly extended to provide a bearing 46 for the yarn spool 47.

With this construction, the attaching plate 35 is permanently secured to the end of the member 36 and the supporting plate 40 and spring 43 are detachably secured to the plate 35, so that they may be easily removed for repair or replacement. It may be noted that the attaching plate 35 and spool bearing 46 are very rarely injured and practically never 30 require replacement.

In the form of our invention shown in Figs. 9-13, each end of the tubular member 50 is provided with two sets of projections 51 and 52. The attaching plate 53 is offset or displaced inwardly at 54 between the points where it engages the edges of the top and bottom of the member 50. The plate 53 is also recessed or notched at its opposite edges as shown at 55 in Fig. 16, and fits between the projections 51 and 52.

The projections 52 extend outward past the outer surface of the plate 53 and constitute guides for positioning the outer or supporting plate 56, while the projections 51 are bent around the displaced portion 54 of the plate 53 and hold the plate firmly in position against the end of the tubular member.

The supporting plate 56 is secured to the 50 outer face of the plate 53 by screws 57, as in the previous form, and is prevented from either lateral or longitudinal displacement by the ears or projections 52. A supporting spring 58 is clamped between the outer faces 55 of the embracing projections 51 and the inner face of the plate 56 and projects upwardly through an elongated slot 59, crossing the slot both at its upper and lower ends. With this construction the spring 60 can be bent backward flat against the attaching plate 53 if necessary, thus affording increased space for movement during attachment to the transporting chain.

Having thus described three forms of our 65 improved bracket and tube frame construc-

tion, it will be seen that they each embody an extremely firm and rigid construction in which the supporting bracket or a portion thereof is secured against the end of the tubular member by bending integral projections on the member around a portion of the bracket. The parts are all preferably formed of steel and are well adapted to withstand the rough usage to which they are at times subjected.

Having thus described our invention and the advantages thereof, we do not wish to be limited to the details herein disclosed otherwise than as set forth in the claims, but what we claim is:

1. A tube frame for looms comprising a tubular member and supporting brackets for said member, each bracket including a rigid spool bearing plate having notches in its side edges and said tubular member having holding portions co-operating directly with the notched edges of said plate to secure said plate firmly and permanently against the end of said member and from displacement longitudinally of said plate, said holding portions and notches forming the entire securing means for said plate.

2. A tube frame for looms comprising a tubular member and supporting brackets for said member, each bracket including a spool bearing plate abutting portions of an end of said tubular member on a plurality of faces thereof and being embraced and held in position by the remaining portions of the end of said tubular member, said plate and tubular member having co-operating portions preventing relative displacement longitudinally of said plate.

3. A tube frame for looms comprising a tubular member and supporting brackets for said member, each bracket including a spool-bearing plate lying flat against the ends of the upper and lower walls of said tubular member and portions of the side walls thereof, and having notches in its side edges receiving outwardly projecting portions of said side walls, said projecting portions being bent to embrace a portion of said bracket and to prevent displacement thereof.

4. A tube frame for looms comprising a tubular member and supporting brackets for said member, each bracket comprising an attaching plate permanently secured in position at an end of the tubular member, a supporting plate detachably secured to said attaching plate, and a spring clamped in position between said attaching and supporting plates.

5. A tube frame for looms comprising a tubular member and supporting brackets for said member, each bracket comprising a spool bearing plate having notches in its side edges, and a supporting plate detachably secured thereto, said tubular member having integral projecting portions extending

through said notches and bent inward to partially embrace and hold said spool-bearing plate in fixed position.

6. A tube frame for looms comprising a tubular member and supporting brackets for said member, each bracket comprising an attaching plate abutting one end of said member and having a portion displaced inwardly of said member, means engaging said displaced portion to permanently secure said plate to said member, a supporting plate detachably secured to said attaching plate, and a spring clamped between said supporting plate and the securing means for said attaching plate.

7. A tube frame for looms comprising a tubular member and supporting brackets for said member, each bracket comprising an attaching plate secured to an end of said member, a supporting plate detachably secured to said attaching plate, and a spring clamped between said plates, and extending upwardly through an elongated slot in said supporting plate, said spring crossing said slot in reverse directions near the upper and lower ends of said slot. 20 25

In testimony whereof we have hereunto affixed our signatures.

JOHN G. SODERBERG.

WILLIAM W. ROBERTSON.
